UNITED STATES PATENT OFFICE

HENRY H. HARRIS, OF DETROIT, MICHIGAN, AND GEORGE C. MCCORMICK, OF NEEDHAM, MASSACHUSETTS, ASSIGNORS TO GENERAL ALLOYS COMPANY, OF BOSTON, MASSACHUSETTS, A CORPORATION OF MASSACHUSETTS

ROLLER RAIL FOR INDUSTRIAL HEATING FURNACES

Application filed September 22, 1930. Serial No. 483,430.

Our invention relates to improvements in rollers and rails for industrial heating furnaces, for example, heat treatment furnaces such as carbonizing furnaces, in which the 5 heavy boxes are pushed through the highly heated furnace while supported on rollers mounted to rotate in the roller rails. The invention includes improvements in the rollers and rails and in the rail mountings within 10 the furnace.

Among the objects of our invention, one is to provide a roller which will run freely with a minimum of side thrust and which is reduced in cross section between the hub and the 15 rim, thereby assuring a sounder and better casting.

Another object is to provide bearing supports for rollers which will prevent the rollers from becoming dislodged when work is 20 passed over them.

Another object is to provide a means for anchoring the rail sections, which will permit expansion of said sections and anchors during high temperatures.

With the foregoing and related objects in view, my invention will be best understood from the illustrative embodiment thereof, shown in the accompanying drawing, in 25 which:

Figure 1 is a section through the hearth of a furnace, showing in elevation the adjacent end parts of two rail sections with rollers mounted therein, and an anchor member for connecting and supporting the said rail 35 sections, embedded in the hearth of the furnace.

Fig. 2 is a vertical sectional view taken on the line 2-2 of Fig. 1;

Fig. 3 is a detail view, partly in section, of 40 a roller, and

Fig. 4 is a transverse sectional view through a rail provided with a modified form of roller and bearing therefor.

We provide a plurality of tracks preferably arranged parallel to one another in the usual manner. Each track comprises a plurality of roller rail sections placed end to end within a furnace, with a plurality of rollers mounted therein over which rollers heat treatment boxes, as for example carbonizing 45

boxes, are passed. Plates or other shapes being heat treated may be put through the furnace, traveling over said rollers if desired. This system is well known in the art, but our invention comprises several inferred features, 55 including a means for positively anchoring the rail sections in such a way as to permit said rails and anchors to expand when subjected to high temperatures, and contract when cooled without resulting distortion or 60 displacement. It also comprises an improved mode of mounting the rollers on said rails, which positively prevents the rollers from being dislodged from their bearings by the moving work, also an improved form 65 of roller and mounting which facilitates free running conditions, eliminating any appreciable amount of friction due to end thrust.

The rail sections 10^a and 10^b are substantially U-shaped, having preferably flattened bases 12 and vertical side walls 14. Angular slots 16 are formed in the upper portions of the vertical walls 14, the angle at which the slots are formed being such that the open or entering ends of the slots are substantially 70 opposed to the direction of the moving work, and said slots are adapted to receive and provide the bearings for pintles 17 of rollers 18. Heretofore the slots for this purpose have been made vertical and were found 75 to be unsatisfactory because there was a tendency for rollers to jump their bearings, when encountered by the work during its progress through the furnace. With the slots on an angle, one corner 20 overlaps the 80 pintles and prevents same from jumping.

In a long furnace each roll comprises rail sections placed end to end with sufficient space between their adjacent ends to permit 85 expansion, and secured to an anchoring member 22, which is embedded in the hearth of a furnace. The anchoring member of our invention comprises a pair of vertically disposed legs 24 joined at the top by a bridging piece 26, having flanges 28 projecting upward therefrom and perpendicular thereto, forming a yoke 29, said anchor also having two feet 30 projecting outwardly at right angles from the lower portion of the legs 24.

Each of the flanges 28 of yoke 29 has an

elongated slot 32 and a hole 34 which register respectively with holes 36 and 38 in walls 14 of the adjacent ends of the rail sections as 10^a, 10^b. The anchoring members 22 are built into the furnace hearth with the bridging piece 26 inserted in the floor with its top flush with the floor, to permit the bottom of the rail sections, supported at their ends on bridging piece 26, to lie flat on the floor bed. 5 Under each foot member 30 of the anchoring members 22 we place a shim of combustible material 40, such as cardboard or the like, which will disintegrate when the first heat is applied in the furnace, the purpose 10 of such shim 40 being to provide a support for the anchor during erection, and upon destruction thereof by application of heat, to provide a clearance and leave the legs 24 free to expand under high temperatures, 15 without distortion or raising and dislodging the bridging piece with attached rails at the joints. After the anchor members 22 are embedded in the furnace floor, track rail sections as 10^a, 10^b are set in place end to end, with the abutting ends thereof lying in the trough of yoke 29 between flanges 28, 28, the holes 36 in an end of the rail section 10^a registering with the elongated slots 32 in the 20 anchor flanges 28, while the holes 38 in the other end of the adjoining rail sections 10^b register with holes 34 in the anchor flanges 28. Pins 42 are inserted in the said registering openings 32, 36 and 34, 38 to secure the said rails 10 to the anchor members 22. 25 It will be understood that the successive joints are formed in the same way, each of the rail sections having a round hole 34 at one end and an elongated slot 32 at its opposite end. A clearance space is left at 30 between the ends of the cold rails and pins 42 are initially at the end of slots 32 furthest from holes 34 to allow the rails to expand in the direction of work travel. When the 35 rails expand, due to the high temperatures, the rail ends with pins 42 in the slots 32 are adapted to move the distance of expansion without distorting said rails and return to normal length when cooled, thereby retaining rail alignment and anchoring member 40 location under all temperature conditions.

The rollers 18 which form a part of our invention are constructed in such a way as to reduce friction by preventing the side of the roller rims from rubbing against the rails. 55 Each roller 18 (Figs. 1, 2 and 3) comprises a rim 44, a hub 46, pintles 17, projecting beyond each side of the hub, and a web 48 joining said hub and rim. To prevent the sides of the roller rims 44 from rubbing against the rails, the hub 46 is preferably made wider than the rim 44 so the sides of the hub will project beyond the sides of the roller rim. Thus the rims never contact with the rail section flanges, and the end thrust is taken up by the faces 50 of the said hub

46 producing very little friction as compared with the sides of the rollers. The pintles 17 being made on a substantially conical taper, as are also the bearing parts of the rail slots, serves to further reduce bearing 70 side thrust and friction.

Another way to produce substantially the same result is shown in the modified form of Fig. 4, which provides bosses 52 to project inwardly from each side wall 14^a of the rail 75 10^a in the region of bearing slots 16, and in such case the roller rim of the rollers 18^a may be the same width as the roller hub 46^a, as the rim is prevented from engaging the rail flanges by engagement of bosses 52 with 80 the hub 46^a.

Having described our invention, what we wish to secure by Letters Patent is set forth in the following claims, it being understood that our invention includes changes which 85 may be resorted to within the scope of our claims:

1. Roller rails for heat treating furnaces, said rails being made in a plurality of sections, means for anchoring the sections in 90 the furnace floor and combustible temporary supports for the anchoring means.

2. Roller rails for use in heat treating furnaces comprising substantially U-shaped rails, angular bearing slots in the side walls 95 thereof and having the open ends thereof directed toward the oncoming work, rollers mounted within said slots, and means for anchoring said rails at their junctures, said means being provided with a slip joint, permitting said supports to expand in a longitudinal direction.

3. Roller rails for use in heat treating furnaces comprising substantially U-shaped rails, angular bearing slots in the side walls 105 thereof and having the open ends thereof directed toward the oncoming work, rollers mounted within said slots, and means for anchoring said rails at their junctures, comprising leg portions embedded in the hearth of a furnace and the exposed upper yoke portion 110 in which the rail junctures are placed, holes in said rail junctures registering with slots and holes in said yoke, and pins inserted in 115 said holes and slots to secure the rails within said yoke with one part of the juncture free to expand and contract.

4. A means for anchoring roller rails at their junctures within a furnace, comprising a yoke having vertical flanges, between which said rails are mounted connecting means between said rail and yoke adapted to permit longitudinal rail expansion, legs extending downwardly from said yoke and having feet 125 at right angles thereto, the legs and feet embedded in a furnace hearth, and means for providing clearance under said feet to permit leg expansion.

5. Device as claimed in claim 4 in which 120

- the clearance providing means consists of combustible temporary supports.
6. A roller for use on roller rails in heat treating furnaces comprising a rim, a hub having end faces extending beyond the sides of said rim, a substantially central web thinner than the rim and connecting said rim and hub, and pintles projecting beyond each side of said hub.
- 10 7. Roller rail apparatus for use in heat treating furnaces comprising rollers, rails adapted to support said rollers, said rollers having projecting bosses to prevent the sides of said rollers from rubbing the rails and causing friction thereagainst, and means for anchoring said rails at their junctures, said means being provided with a slip joint, permitting said supports to expand in a longitudinal direction.
- 20 8. Rails for industrial furnaces having slots therein arranged at an angle to face the movement of the work, and rollers mounted in said slots.
9. Roller rails for use in heat treating furnaces comprising a plurality of aligned rail sections, and an anchoring member embedded in the furnace floor and engaging said sections at contiguous ends thereof.
- 30 10. Roller rails for use in heat treating furnaces comprising a plurality of aligned rail sections, and anchoring means connecting said rail sections at the juncture thereof, the connection allowing relative expansion and contraction of said sections with temperature changes.
- 40 11. Roller rails for use in heat treating furnaces comprising a plurality of aligned rail sections, and anchoring means embedded in the furnace floor and connecting said sections at the juncture thereof, the connection allowing relative expansion and contraction of said sections as the temperature varies.
- 45 12. Roller rails for use in heat treating furnaces comprising a plurality of aligned rail sections, and anchoring means embedded in the furnace floor and connecting said sections at the juncture thereof, said anchoring means having provision for allowing expansion thereof without dislocating said rail sections.
- 50 13. Roller rails for use in heat treating furnaces comprising a plurality of aligned rail sections, and anchoring means embedded in the furnace floor and connecting said sections to allow relative expansion and contraction thereof, said anchoring means also including provision for allowing expansion thereof without dislocating the rail sections.
- 60 14. Roller rails for use in heat treating furnaces comprising a plurality of aligned rail sections, and an anchoring member having angular legs embedded in the furnace floor and a portion engaging said sections at the juncture thereof for retaining the same in place.
15. Roller rails for use in heat treating furnaces comprising a plurality of aligned rail sections, and an anchoring member having angular legs embedded in the furnace floor and a yoke portion receiving said rail sections at the juncture thereof.
- 70 16. Roller rails for use in heat treating furnaces comprising a plurality of aligned rail sections, and an anchoring member having angular legs embedded in the furnace floor and a yoke portion receiving said rail sections at the juncture thereof, said rail sections being connected to said yoke portion to allow relative expansion and contraction of said sections.
- 80 17. Roller rails for use in heat treating furnaces comprising a plurality of aligned U-shaped rail sections, and an anchoring member embedded in the furnace floor and having yoke portion receiving the sections at the juncture thereof.
- 85 18. Roller rails for use in heat treating furnaces comprising a plurality of aligned U-shaped rail sections, and an anchoring member embedded in the furnace floor and having a yoke portion receiving the sections at the juncture thereof, the lateral walls of said yoke portion and said rail sections being connected to allow relative expansion and contraction of the rail sections.
- 90 19. Roller rails for use in heat treating furnaces comprising a plurality of aligned rail sections, and anchoring members embedded in the furnace floor and engaging said rail sections at the junctures thereof, one end of each rail section being connected to an anchoring member to prevent bodily movement of the rail section relative thereto and the other end of each rail section being free to expand and contract longitudinally relative to another anchoring member.
- 100 20. Roller rails for use in heat treating furnaces comprising a plurality of aligned rail sections, and an anchoring member embedded in the furnace floor and connected to said rail sections at the juncture thereof, one of said connections being slotted to allow longitudinal expansion of a rail section.
- 105 21. Roller rails for use in heat treating furnaces comprising a plurality of aligned rail sections, and an anchoring member embedded in the furnace floor and connected to said rail sections at the juncture thereof, one of said connections being slotted to allow longitudinal expansion of a rail section in the direction of work travel.
- 110 22. Roller rails for use in heat treating furnaces comprising a plurality of U-shaped rail sections and an anchoring member including leg portions embedded in the floor of the furnace and an exposed yoke portion having the base thereof flush with the furnace floor and receiving the ends of the rail sections, said rail sections being connected to
- 115
- 120
- 125
- 130

said yoke portion to allow relative longitudinal expansion of the rail sections, and said leg portions also being free to expand without displacing the base thereof.

5 In testimony whereof we have signed our names hereto.

HENRY H. HARRIS.
GEO. C. McCORMICK.
